US00D615073S

(12) **United States Design Patent**
Maloney et al.

(10) **Patent No.:** US D615,073 S
(45) **Date of Patent:** ** May 4, 2010

(54) **TELECOMMUNICATIONS DISTRIBUTION CLOSURE**

(75) Inventors: **Jerome A. Maloney**, Sugar Grove, IL (US); **Eduardo Leon**, Woodridge, IL (US); **Simon Shen-Meng Chen**, Palatine, IL (US); **George I. Wakileh**, Batavia, IL (US)

(73) Assignee: **Emerson Network Power, Energy Systems, North America, Inc.**, Warrenville, IL (US)

(**) Term: **14 Years**

(21) Appl. No.: **29/284,702**

(22) Filed: **Sep. 13, 2007**

(51) **LOC (9) Cl.** 14-03

(52) **U.S. Cl.** D14/240

(58) **Field of Classification Search** D14/240; D13/184; 385/133-139; 312/223.1, 223.2, 312/265.2-265.4; 361/730, 823

(57) **CLAIM**

The ornamental design for a telecommunications distribution closure, as shown and described.

DESCRIPTION

FIG. 1 is a front view of the telecommunications distribution closure;

FIG. 2 is a rear view thereof;

FIG. 3 is a top view thereof;

FIG. 4 is a right side view thereof;

FIG. 5 is a left side view thereof; and,

FIG. 6 is a front perspective view thereof.

The broken lines shown in FIGS. 4 and 5 are included for the purpose of illustrating boundaries that form no part of the claimed design.
